No. 36,957.

Patented June 7, 1904.

UNITED STATES PATENT OFFICE.

WILLIAM HELMER, OF BOSTON, MASSACHUSETTS.

DESIGN FOR A CREAM-WHIPPER BOWL AND COVER.

SPECIFICATION forming part of Design No. 36,957, dated June 7, 1904.

Application filed January 25, 1904. Serial No. 190,633. Term of patent 3½ years.

To all whom it may concern:

Be it known that I, WILLIAM HELMER, a citizen of the United States, residing at Boston, in the county of Suffolk and State of Massachusetts, have invented a new, original, and ornamental Design for a Cream - Whipper Bowl and Cover, of which the following is a specification, reference being had to the accompanying drawings, forming a part hereof, in which—horizontal section, of a cream-whipper bowl and cover embodying my new and ornamental design.

What I claim as new, and desire to secure 15 by Letters Patent, is—

The ornamental design for a cream-whipper bowl and cover, as herein shown.

WILLIAM HELMER.
